US00D937317S

(12) **United States Design Patent** (10) **Patent No.:** **US D937,317 S**
Altonen et al. (45) **Date of Patent:** **** Nov. 30, 2021**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Gregory S. Altonen**, Easton, PA (US);
Jason C. Killo, Emmaus, PA (US);
Brad M. Kreschollek, Bethlehem, PA (US);
Madia L. Rivera, Bethlehem, PA (US)

(73) Assignee: **Lutron Technology Company LLC**,
Coopersburg, PA (US)

(**) Term: **15 Years**

(21) Appl. No.: **29/719,578**

(22) Filed: **Jan. 6, 2020**

Related U.S. Application Data

(63) Continuation of application No. 29/633,663, filed on Jan. 15, 2018, now Pat. No. Des. 872,122.

CLAIM

We claim the ornamental design for a display screen or portion thereof with graphical user interface, as shown and described.

DESCRIPTION

The sole FIGURE shows a display screen or portion thereof with graphical user interface according to our new design. The peripheral dashed broken lines illustrate a display screen or portion thereof or sheet material, and form no part of the claimed design.

1 Claim, 1 Drawing Sheet
